SHOE TREE

Edmund J. Baas, Rochester, N. Y., assignor to Rochester Shoe Tree Co. Inc., Rochester, N. Y., a corporation of New York

Application August 20, 1953, Serial No. 26,527

Term of patent 7 years

(Cl. D7—3)

To all whom it may concern:

Be it known that I, Edmund J. Baas, a citizen of the United States, residing in Rochester, in the county of Monroe and State of New York, have invented a new, original, and ornamental Design for a Shoe Tree, of which the following is a specification, reference being had to the accompanying drawings, forming a part hereof.

Fig. 1 is a perspective view of a shoe tree showing my new design;

Fig. 2 is a side elevation of the handle portion of the shoe tree;

Fig. 3 is a top view of Fig. 2;

Fig. 4 is an end view looking from the right of Fig. 2; and

Fig. 5 is an end view looking from the left of Fig. 2.

The characteristic feature of the design resides in the solid line portion.

I claim:

The ornamental design for a shoe tree, substantially as shown and described.

EDMUND J. BAAS.
